UNITED STATES PATENT OFFICE.

JOHN F. McHENRY, OF CAMERON, MISSOURI.

DESIGN FOR A LAMP-CHIMNEY.

SPECIFICATION forming part of Design No. 33,553, dated November 13, 1900.

Application filed June 1, 1900. Serial No. 18,781. Term of patent 14 years.

To all whom it may concern:

Be it known that I, JOHN F. McHENRY, a citizen of the United States, residing at Cameron, in the county of Clinton and State of Missouri, have invented and produced a new and useful Design for Lamp-Chimneys, of which the following is a specification, reference being had to the accompanying drawings, in which—

Figure 1 is a perspective view of a lamp-chimney constructed in accordance with my design, and Fig. 2 is a vertical longitudinal section of the same.

The essential feature of my invention resides in the peculiar form or shape of the lower end or base of the chimney.

Referring to the drawings, A indicates the chimney proper, the body being swelled or enlarged, as shown at B. Toward the bottom of the chimney the swelled portion is contracted, and between the points C and D the sides of the chimney are given a decided inward curve, and between the points D and E

the sides are swelled or curved outwardly, and between the points E and F are rounded 25 and brought inwardly to the bottom of the chimney, thus producing a gradual incurve between the points C and D and a gradual swell or outward curve between the points D and F. It will thus be seen that I provide a 30 lamp-chimney the base or lower end of which is slightly enlarged, swelled, and rounded, and that portion of the chimney directly above said base is slightly contracted, thereby making the curved and swelled base stand 35 out more prominently.

Having thus fully described my invention, what I claim as new, and desire to secure by Letters Patent, is—

The design for a lamp-chimney, substantially as herein shown and described. 40

JOHN F. McHENRY.
